CENTRIFUGAL PUMP

Filed March 4, 1932

FIG. 2. Inventor
John W. W. Drysdale,
By William C. Linton,
Attorney.

UNITED STATES PATENT OFFICE

JOHN WHITEHEAD WILSON DRYSDALE, OF YOKER, GLASGOW, SCOTLAND, ASSIGNOR TO
DRYSDALE AND COMPANY, LIMITED, OF YOKER, GLASGOW, SCOTLAND

CENTRIFUGAL PUMP

Application filed March 4, 1932, Serial No. 596,870, and in Great Britain March 30, 1931.

This invention relates to centrifugal pumps of the self-priming type comprising essentially an impeller (or impellers) rotatable about a vertical axis, an air-separating chamber, an air-exhauster preferably of the water-ring type for extracting the air from said chamber, and a driving motor coupled to the impeller and to the air-exhauster.

The invention will be defined in the annexed claims. For convenience it may here be said that the invention in fact consists in a new and improved construction characterized by the provision of a passage in the form of a loop interposed between the main suction 15 inlet and the eye of the water-impeller, said passage comprising ascending and descending branches separated by an inclined partition or weir overhanging the ascending branch and presenting an air trap.

20 Preferably the motor is disposed above the impeller, and the air-exhauster located between the motor and the water-impeller, or above the motor.

Desirably the water-impeller is of the single-entry type, with the suction eye looking upwards, thus avoiding the possibility of air-lock at the impeller eye and permitting the air to vent upwards.

In practice, the inclined partition or weir is formed at the upper edge with an over-turned lip adapted to trap the ascending air. Water entering at the main suction inlet and rising in the ascending branch of the passage overhung by the inclined partition or weir flows over the lip and thence to the eye of the impeller.

Side vents lead from the air trap to the upper part of the separating chamber, air caught in the trap escaping gradually to the 40 top of the chamber without being interfered with by the main current of water.

With the described arrangement there is realized the maximum of air separation from the water and hence increased efficiency of the 45 pump when handling water which is charged with air, whether due to air leaks in the suction pipe or entrained in the process of priming.

The liberation of air from the upper part of the separating chamber is controlled by a

float-operated valve housed in a valve compartment.

A pipe leads from the valve compartment to the suction compartment of an air exhaust- 55 er of the water ring type incorporating a runner rotating within a vortex chamber surrounded by a water jacket and having controlled connections whereby the water constituting the water ring may be forced out of the vortex chamber and delivered to a res- 60 ervoir, when it is desired to cut the air-ex- hauster out of action.

The runner of the air-exhauster may be provided on its under side with a set of radial vanes, ensuring that a suitable back pressure 65 is maintained from the ring vortex and effectively preventing air leakage.

The runner is desirably formed integral with a bush which extends above the level of the water in the air-exhauster casing and thus 70 prevents water leakage from the exhauster whether the pump is standing or running.

In the case where the air-exhauster is situated between the motor and the water-impeller there may be provided on the driving side 75 of the exhauster adjoining the motor coupling a plain neck bush constructed with suitable clearance and adapted to form a water seal which comes into action whenever the air exhauster is exercising suction and thus prevents air leakage during working.

A centrifugal pump constructed in accordance with the invention is illustrated more or less diagrammatically in the accompanying drawing, in which Fig. 1 is a part vertical 85 section, part elevation, Fig. 2 a section on the line 2-2 of Fig. 1, and Figs. 3 and 4 are fragmentary horizontal sections.

The centrifugal pump shown comprises a water-impeller 1 rotatable about a vertical 90 axis, a driving motor 2 to which the water-impeller 1 is coupled, an air-separating chamber 3, and an air-exhauster of the water-ring type indicated generally at 4, also coupled to the motor 2, for extracting the air 95 from the chamber 3.

The impeller 1 is of the single-entry type with the suction eye 5 looking upwards.

Interposed between the main suction inlet 6 and the eye 5 is a passage in the form of 100

a loop comprising ascending and descending branches 7, 8 respectively, separated by an inclined partition or weir 9 overhanging the ascending branch 7 and formed at the upper 5 edge with a downturned lip 10 forming an air trap 11. Water entering at the main suction inlet 6 and rising in the ascending branch 7 flows over the lip 10 and down the descending branch 8 to the suction eye 5. Air 10 passing up from the suction inlet 6 and travelling along the lower side of the partition or weir 9 is caught in the air trap 11.

Side vents 13 lead from the air trap 11 to the upper part of the chamber 3, air caught 15 in the trap 11 escaping gradually to the top of said chamber without being interfered with by the main current of water.

The liberation of air from the chamber 3 is controlled by a valve 14 housed in a compartment 20 and operated by a float 15 exercising a powerful leverage; any tendency to back-lash or undue wear of the parts being avoided by the provision of ample trunnion supports at 16 for the float lever 17 25 the free end of which coacts with stops 18, 19.

Any sediment contained in the water near the surface is prevented from gaining access to the compartment 20 by the provision of a cylindrical strainer 21 which houses the 30 working parts of the float mechanism, thus effectively avoiding damage to the float mechanism and ensuring freedom from leakage caused by solid material lodging between the air valve 14 and its seat.

35 A pipe 22 leads from the outlet side of the valve compartment 20 to the suction compartment 23 of the air-exhauster 4, which may be of known construction and which in the form illustrated includes a vaned runner 24 operating in an eccentric or vortex chamber 25. The chamber 25 communicates by way of a suction port 231 (Figs. 3 and 4) with the compartment 23 and by way of a discharge port 232 with a discharge compartment (not shown) adjacent to the compartment 23. As is understood, the vortex chamber 25 contains water which is caused by the rotation of the runner 24 to adhere to the sides of the chamber 25 and thus to leave the 50 axis of rotation of the runner 24. There are thus left in the intervane spaces of the runner 24 cavities which expand and contract alternately, the suction port 231 being open to the expanding cavities and the discharge 55 port 232 being open to the contracting cavities.

The vortex chamber 25 is water-jacketed by a cooling-water pocket 26 (Figs. 3 and 4) and by a sealing-water reservoir 27 for the 60 air exhauster. Cooling water is circulated through the pocket 26 by way of connections 261, 262 connected, respectively, to the centrifugal pump suction and to the centrifugal pump discharge by way of pipes, not shown. 65 The discharge compartment of the air-ex-

hauster is connected to the water reservoir 27 by way of a port 28 through which water entrained by the air discharged by the exhauster is drained back to the reservoir 27. 70 29 denotes a make-up water supply duct connecting the reservoir 27 to the under side of the runner 24. Fitted to the water jacket is a switch-cock shown only in Figs. 3 and 4 including a plug 30 rotatable in a cock-body 31. The plug 30 is provided with ports 32, 75 33 adapted to co-operate with ports 34, 35, respectively in the plug-body 31. The plug port 32 is continuously connected to a passage 36 communicating with the interior of the chamber 25. The port 34 registers with a 80 port 341 communicating with the reservoir 27. The port 35 is connected by way of a pipe not shown to the suction compartment 23 of the air exhauster.

271 denotes an overflow pipe fitted within 85 the reservoir 27.

When the plug 30 is in the position shown in Fig. 3, the water constituting the water ring is discharged from the chamber 25 by way of the passage 36, and ports 32, 34, 90 and 341 into the reservoir 27, so as to cut the exhauster out of action, atmospheric air being admitted by way of the ports 33, 35 to the suction compartment 23 whereby to break the vacuum therein. When the plug 30 is in 95 the position shown in Fig. 4, all the ports are masked so that the exhauster is permitted to function normally.

The runner 24 is unitary with a bush 37 extending above the level of the water in the 100 exhauster casing and surrounding with clearance a bearing bush 38 embracing the intermediate portion 40 of the shaft 39-41, the arrangement being such that there is afforded between the bushes 37, 38 a water seal 105 which comes into action whenever the exhauster is exercising suction and thus prevents air leakage during operation.

Having thus described my invention, what I claim as new and desire to secure by Letters Patent is:-

1. A centrifugal pump of the self-priming type comprising a water-impeller arranged to rotate about a vertical axis, an air-separating chamber, an air-exhauster for extracting the air from said chamber and mounted above the said water-impeller, and a driving motor mounted above and coupled to the water-impeller and to the exhauster, a passage in the form of a loop interposed 115 between the main suction inlet and the eye of the water-impeller, said passage comprising ascending and descending branches, an inclined partition separating the two branches and forming at its top a weir which overhangs the ascending branch.

2. A centrifugal pump of the self-priming type comprising a water-impeller arranged to rotate about a vertical axis, an air-separating chamber, an air-exhauster for extracting 130

the air from said chamber and mounted above the said water-impeller, and a driving motor mounted above and coupled to the water-impeller and to the exhauster, a passage 5 in the form of a loop interposed between the main suction inlet and the eye of the water-impeller, said passage comprising ascending and descending branches, an inclined partition separating the two branches and forming 10 at its top a weir which overhangs the ascending branch, the weir being provided with an overturned lip adapted to trap the ascending air.

3. A centrifugal pump of the self-priming 15 type comprising a water-impeller arranged to rotate about a vertical axis, an air-separating chamber, an air-exhauster for extracting the air from said chamber and mounted above the said water impeller, and a driving 20 motor mounted above and coupled to the water-impeller and to the exhauster, a passage in the form of a loop interposed between the main suction inlet and the eye of the water-impeller, said passage comprising ascending 25 and descending branches, an inclined partition separating the two branches and forming at its top a weir which overhangs the ascending branch, the weir being provided with an overturned lip adapted to trap the ascending 30 air, side vents leading from the hollow below the overturned lip to the top of the air-separating chamber.

4. A centrifugal pump of the self-priming type comprising a water-impeller arranged 35 to rotate about a vertical axis, an air-separating chamber, an air-exhauster for extracting the air from said chamber, a driving motor coupled to the water-impeller and to the exhauster, and a passage in the form of a loop 40 interposed between the main suction inlet and the eye of the water-impeller, said passage comprising ascending and descending branches, and an inclined partition separating said branches and forming at its top a 45 weir which overhangs the ascending branch and affords an air trap and connections between said air trap and said separating chamber.

I hereby sign my name to this specification.
50 JOHN WHITEHEAD WILSON DRYSDALE.
